(57) **CLAIM**

The ornamental design for a stainless steel insulated cup, as shown and described.

DESCRIPTION

FIG. 1 is a front, right, top perspective view of the stainless steel insulated cup in the first state, showing my new design; FIG. 2 is a rear, left, bottom perspective view thereof; FIG. 3 is a front elevational view thereof; FIG. 4 is a rear elevational view thereof; FIG. 5 is a left side view thereof; FIG. 6 is a right side view thereof; FIG. 7 is a top plan view of the enlarged scale thereof; FIG. 8 is a bottom plan view of the enlarged scale thereof; and, FIG. 9 is a front, right, top perspective view of the stainless steel insulated cup in the second state. The dashed broken lines in the figures illustrate portions of the stainless steel insulated cup that form no part of the claimed design.

1 Claim, 9 Drawing Sheets
